W. L. BEAN

LOCOMOTIVE SMOKE BOX AND SADDLE CONSTRUCTION

Original Filed March 5, 1925

Inventor:
William L. Bean,
Assignee: Santa Fe Railway
Attest

UNITED STATES PATENT OFFICE.

WILLIAM L. BEAN, OF WEST HAVEN, CONNECTICUT.

LOCOMOTIVE SMOKE-BOX AND SADDLE CONSTRUCTIONS.

Original application filed March 5, 1925, Serial No. 13,242. Divided and this application filed April 2, 1926. Serial No. 99,415.

This invention relates to a novel locomotive smoke-box saddle construction. The invention will be best understood by reference to the following description, when taken in connection with the accompanying drawings of one specific embodiment thereof, while its scope will be more particularly pointed out in the appended claims.

In the drawings:

Fig. 1 is a central, vertical, longitudinal, sectional view of a portion of the front end of a locomotive, including the cylinder saddle and the smoke box thereon; and

Fig. 2 is a bottom plan of a portion of a locomotive, including the cylinder saddle and the smoke box thereon; and.

Referring to the drawings, and to the embodiment of the invention which is selected for exemplification, and having reference more particularly to Fig. 1, the locomotive has a cylinder saddle 20, which presents a support for a smoke box 21. Relative displacement of the smoke box and the saddle in a horizontal direction is prevented by interengagement of these parts, which prevents the attaching bolts from being subjected to any shearing stresses.

In the present example, this is conveniently accomplished by providing the smoke box with front and rear abutments, presented by depending flanges 22, which receive the forward and backward thrusts, said smoke box presenting similar side flanges 23, which receive the side thrusts, all of which flanges embrace a seat 24, presented by the cylinder saddle. Herein, the seat is flat,—that is to say, it is a plane horizontal surface, and a corresponding surface 25 of the smoke box, which rests upon it, is a plane surface. This is preferred, as it facilitates the machining and fitting together of these parts. The machining of the surface 25 is further facilitated by making the front and rear flanges 22 separated from the side flanges 23 by spaces 26 (see Fig. 2).

The smoke box presents an opening 27 for an exhaust pipe 28. In the present instance, front and rear flanges have a length not greater than the horizontal dimension of this opening, transversely of the smoke box, and the side flanges have a length no greater than the horizontal dimension of the opening longitudinally of the smoke box. This construction permits the surface 25 to be machined conveniently by planing,

or by the use of a milling cutter, as will be evident from an examination of Fig. 2. The smoke box is suitably secured to the cylinder saddle, as by bolts 29 having nuts 30, which are on the outside of the smoke box where they are not subject to the abrasive and corrosive action of the cylinders and products of combustion, and where they are readily accessible for removal in case at any time it should become necessary or desirable to remove the smoke box from its seat on the cylinder saddle.

This application is a division of my pending application for locomotive smoke boxes and draft appliances, Ser. No. 13,242, filed March 5, 1925.

Having thus described one embodiment of the invention, but without limiting myself thereto, what I claim and desire by Letters Patent to secure is:

1. In a locomotive, the combination of a cylinder saddle and a smoke-box interengaging with each other and held against relative displacement in a horizontal direction by reason of their interengagement, and means rigidly attaching said smoke-box to said saddle.

2. In a locomotive, the combination of a cylinder saddle and a smoke-box, one presenting abutments by which the other is held against displacement in a horizontal direction relatively thereto, and means to hold said saddle and smoke-box against relative vertical displacement.

3. In a locomotive, the combination of a saddle and a smoke-box, the latter presenting front and rear abutments between which a portion of the former is received.

4. In a locomotive, the combination of a steam pipe, a cylinder saddle secured to said pipe, and a smoke-box connected with said pipe and interengaging with said saddle and held thereby against displacement horizontally both longitudinally and transversely of the locomotive and in turn holding said pipe against horizontal displacement.

5. In a locomotive, the combination of a saddle and a smoke-box, one presenting abutments by which the other is held against displacement in a horizontal direction longitudinally of the locomotive, and one presenting abutments by which the other is held against displacement in a horizontal direction transversely of the locomotive.

6. In a locomotive, the combination of a

- saddle and a smoke-box, presenting front and rear and lateral abutting surfaces by which said saddle and smoke-box are held against relative horizontal displacement both longitudinally and transversely of the locomotive.
7. In a locomotive, the combination of a saddle and a smoke-box, the latter presenting front and rear and side flanges between which a portion of said saddle is received, and by which relative horizontal displacement of said saddle and smoke-box longitudinally and transversely of the locomotive is prevented.
8. In a locomotive, the combination of a cylinder saddle and a smoke-box having plane surfaces, one resting on the other, and means rigidly attaching said saddle and smoke-box together.
9. In a locomotive, the combination of a saddle and a smoke-box having plane, horizontal surfaces, one resting on the other, said saddle and smoke-box interengaging with each other and held against relative horizontal displacement in every direction by reason of their interengagement.
10. In a locomotive, the combination of a saddle and a smoke-box having plane, horizontal surfaces, one resting on the other, one of said parts presenting abutments by which the other is held against horizontal displacement in every direction relatively thereto.
11. In a locomotive, the combination of a saddle and a smoke-box having plane, horizontal surfaces, one resting on the other, one of said parts presenting abutments by which the other is held against displacement in a horizontal direction relatively thereto longitudinally of the locomotive, and one of said parts presenting abutments by which the other is held against displacement in a horizontal direction relatively thereto transversely of the locomotive.
12. In a locomotive, the combination of a saddle and smoke-box having plane, horizontal surfaces, one resting on the other, said smoke-box presenting front and rear flanges and side flanges between which a portion of said saddle is received.
13. In a locomotive, the combination of a saddle and a smoke-box having plane, horizontal surfaces, one resting on the other, said smoke-box presenting pairs of front and rear and side flanges between which a portion of said saddle is received, the front and rear flanges being separated from the side flanges by spaces.
14. In a locomotive, the combination of a saddle and a smoke-box having plane, horizontal surfaces, one resting on the other, said smoke-box presenting pairs of front and rear and side flanges between which a portion of said saddle is received, the length of each front and rear flange being less than the dimension of said horizontal surface of said smoke-box transversely of the latter, and the length of each side flange being less than the dimension of said horizontal surface of said smoke-box longitudinally of the latter.
15. In a locomotive, the combination of a saddle having a plane, horizontal surface, and a smoke-box having an opening and a plane, horizontal surface about said opening and resting on the horizontal surface of said saddle, said smoke-box presenting pairs of front and rear and side flanges embracing a portion of said saddle, the front and rear flanges having a length no greater than the horizontal dimension of said opening transversely of said smoke-box, and the side flanges having a length no greater than the horizontal dimension of said opening longitudinally of said smoke-box.
16. In a locomotive, the combination of a saddle and a smoke-box, the latter presenting an opening, and a pipe secured to said saddle and extending through said opening into said smoke-box, said saddle and smoke-box interengaging with each other about said opening and independently of said pipe and being held against relative displacement horizontally by reason of their interengagement.
17. In a locomotive, the combination of a saddle and a smoke-box, the latter presenting an opening, said saddle and smoke-box interengaging with each other about and independently of said opening and being held against relative horizontal displacement by reason of their interengagement.
18. In a locomotive, the combination of a saddle and a smoke-box, the latter presenting an opening, said saddle and smoke-box interengaging with each other about and independently of said opening and being held against relative horizontal displacement by reason of their interengagement, said saddle presenting a hollow projection extending into and spaced from the sides of said opening.

In testimony whereof, I have signed my name to this specification.

WILLIAM L. BEAN.
